(57) CLAIM

The ornamental design for a toe spacer and relaxation device, substantially as shown and described.

DESCRIPTION

FIG. 1 is a top rear perspective view of a toe spacer and relaxation device in accordance with the present design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines in the Figures show portions of the toe spacer and relaxation device which form no part of the claimed design.

1 Claim, 4 Drawing Sheets
